UNITED STATES PATENT OFFICE.

HENRY B. STEVENS, OF BUFFALO, NEW YORK, ASSIGNOR TO GEORGE L. SQUIER, OF SAME PLACE.

EVAPORATOR.

SPECIFICATION forming part of Letters Patent No. 268,310, dated November 28, 1882.

Application filed September 29, 1882. (No model.)

To all whom it may concern:

Be it known that I, HENRY B. STEVENS, of the city of Buffalo, in the county of Erie and State of New York, have invented new and useful Improvements in Evaporators, of which the following is a specification.

This invention relates to certain improvements in evaporators for saccharine juices and other liquids, and has for its object to produce an evaporator which is durable and not liable to leak, which is easily and quickly skimmed, which defecates thoroughly, and evaporates rapidly without scorching the sirup.

My invention consists, to that end, of the constructions which are hereinafter fully described, and pointed out in the claims.

In the accompanying drawings, consisting of two sheets, Figure 1 is a perspective view of an evaporator provided with my improvements. Fig. 2 is a longitudinal section, and Fig. 3 a top plan view, thereof. Fig. 4 is a cross-section, on an enlarged scale, in line *x x*, Fig. 3, looking toward the right. Fig. 5 is a longitudinal vertical section of the central portion of the pan. Fig. 6 is a sectional elevation of one of the round corners of the pan. Fig. 7 is a cross-section of the evaporating-pan in line *y y*, Fig. 3, looking toward the left.

Like letters of reference refer to like parts in the several figures.

The evaporating-pan is composed of two separate portions secured together side by side, each consisting of metallic end plates, *A A'*, made preferably of cast-iron, and an outer wall, *A²*, inner wall, *A³*, and a bottom, *A⁴*, all composed in each portion of the pan of a single plate of sheet metal, preferably iron or copper, bent to the proper form, as clearly shown in Fig. 4. The two portions of the pan are secured together by means of rivets or bolts passing through their contiguous inner walls, *A³*. The outer walls, *A²*, are made flaring to prevent boiling over and facilitate skimming, and their outer edges are preferably stiffened by angle-irons secured to the same. The inner walls, *A³*, constitute a longitudinal partition extending from end to end of the evaporator, which stiffens the bottom of the pan and prevents it from warping, and which divides the pan into two longitudinal compartments. The end plates, *A A'*, are constructed with

flanges, to which the plate constituting the body of each portion of the pan is riveted, and the plates *A A'* themselves are secured together near the top by bolts *a* passing through lugs *a'*, formed on said plates.

b represents a tubular passage cast with each end plate *A*, and opening at one end on the inner side of the plate and at the other end on the outside of the plate, the outer opening being on the inner edge of the plate and in line with the other, so that both openings will register or coincide when the two portions of the pan are secured together, and thus establish a conduit or passage on the outer sides of the plates *A* from one longitudinal compartment of the pan to the other. *b'* is a bolt which extends through both parts *b* of the passage, and secures the plates *A* together near the bottom.

c is a transverse partition formed in the second compartment of the pan, which latter is composed of the defecating-compartment *D*, extending from end to end of the pan, a concentrating-apartment, *E*, extending from the end wall *A* to the partition *c*, and a finishing-compartment, *F*, extending from the partition *c* to the end wall *A'*.

g is a movable gate, which is arranged at the mouth of the passage *b* in the compartment *D*, and whereby said passage can be opened and closed at desire.

h represents a similar gate, arranged to open and close an opening, *h'*, formed in the partition *c*. The openings to which these gates are applied are provided with a raised rim or flange, *i*, which surrounds the opening, and is planed off, and the gates are provided with plane blocks *k*, which fit snugly against the plane rims *i*, so as to form a water-tight joint. The blocks *k* are attached to the lower ends of pivoted levers, whereby they can be moved, so as to open or close the respective openings to which they are applied. These gates are very simple in construction and do not leak, and are easily manipulated.

The evaporating-pan is in this manner constructed wholly of metal, with no joints between the bottom and sides, and water-tight joints at the ends and between the compartments, in which latter the three operations of defecating, evaporating, and finishing can be carried on separately, and which can be easily

cleaned, and the principal disadvantages of evaporators constructed with wooden sides and ends, and which consist in the wood absorbing juice, which sours, and in the leakage at the joints, are thereby entirely avoided.

It is desirable to maintain such a circulation through the defecating and evaporating compartments D and E that all the scum is carried to one part of the defecating-compartment, whence it can be easily removed. In order to obtain this result, the partition separating the evaporating-compartment E from the defecating-compartment D is cut down, as shown at l, to a depth which will permit the scum and other light impurities which rise to the surface in the evaporating-compartment E to flow over into the defecating-compartment, in which they are carried by the surface current to the opposite or coolest end of the defecating-compartment. The low portion, l, of the central partition is preferably located near the end, and is preferably about twelve to fifteen inches long and three to four inches below the top of the partition. In order to bring the juice speedily to the boiling-point, the front portion of the evaporating-compartment E is covered by a plate, M, which may, if desired, cover the entire compartment, and the front portion of the defecating-compartment is similarly covered by a plate, N, which extends backward about the same distance as the plate M. These plates confine the steam and reflect the heat, and accelerate the ebullition, whereby the impurities are thrown to the surface and carried off before they are again boiled into the juice, and whereby the inversion of the cane-sugar into grape-sugar, which increases with the length of time the sugar is exposed to the heat, is to a large extent avoided.

The covers M and N are preferably hinged to the longitudinal partition A³, so that they can be readily raised, when required, for regulating the circulation or cleaning of the pan. To prevent the scum from gathering in the corners, they may be provided with curved metallic plates n, as represented in Figs. 3 and 7, or with wooden blocks having concave faces.

O represents the furnace under the evaporator, and P is a longitudinal partition arranged centrally under the rear portion of the pan, and separating the flue p under the defecating-compartment D from the flue p' under the finishing-compartment.

q is the chimney with which both flues communicate, and each flue is provided with a damper, q², whereby the heat can be directed more or less under one or the other compartment, as may be necessary.

The juice to be evaporated is introduced at the rear end of the compartment D, either in a continuous stream or intermittently. The heat is so graduated under the compartment D that this is the coolest part of the pan; but when the heat should be too low in starting the evaporator a removable partition may be placed transversely in the compartment D, over the damper under the compartment, to confine

the raw juice until properly defecated; but when the pan is working properly no such partition is necessary. In this compartment the juice is slowly brought to the boiling-point, and the scum thrown up and carried by the surface current back to the rear end of the compartment, whence it is removed by a skimmer or by a scum-trough extending into the compartment. As the juice becomes clarified and heated it passes forward under the cover N and over the grates, where the heat is strongest, and here it boils. The boiling juice then passes through the tube b into the compartment E, where it boils violently. The steam generated here is confined by the cover M and compelled to pass out through the opening formed by the low portion, l, of the partition. This produces a strong surface current from the compartment E into the compartment D, whereby all the scum is carried from the compartment E into the compartment D. By closing the gate g entirely or partially the circulation can be stopped or regulated, and the whole process is completely under the control of the operator. The defecated juice passes on the bottom of the compartment D to the passage b, and through the latter into the compartment E, when the high heat throws to the surface the impurities which have not been removed before, and the hot current passes near the surface backward to the inlet end of the compartment D. When the juice is sufficiently evaporated for finishing the gate h is opened, when the juice passes into the compartment F. At this stage of the process arises the danger of scorching; but the heat is easily controlled and scorching prevented by the dampers in the flues. When the juice has been finished it is drawn off through the spout r.

I am aware that heretofore covers have been used on evaporators, and that round corner-pieces have been used, also that the longitudinal partition has been reduced in height to permit the overflow of the scum from one compartment into the other, and I do not claim either of these constructions by itself; but

I claim as my invention—

1. In an evaporator, the combination of a defecating-compartment, D, an evaporating-compartment, E, a scum-passage, l, formed in the partition between the two compartments, and a cover, M, applied to the evaporating-compartment E, substantially as set forth.

2. In an evaporator, the combination of a defecating-compartment, D, an evaporating-compartment, E, a scum-passage, l, formed in the partition between the two compartments, a cover, M, applied to the evaporating-compartment, and a cover, N, applied to the defecating-compartment, substantially as set forth.

3. The end plates, A A', constructed with the divided passage b, substantially as set forth.

4. The combination, with the defecating-compartment D, of the evaporating-compartment E, a passage, b, connecting both compartments near their bottoms, a scum-passage, l, formed in the top of the partition between the two com-

partments, and a cover, M, applied to the evaporating-compartment D, substantially as set forth.

5. The combination, in an evaporator, of an opening leading from one compartment into another, a raised flange, i, surrounding said opening and having a plane face, and a movable gate provided with a plane block, k, fitting against the face of the flange i, substantially as set forth.

6. In an evaporator, the combination, with the longitudinal partition A³, of the covers M and N, hinged to said partition, substantially as set forth.

15 7. The combination of the compartments D, E, and F, the passage b, connecting the compartments D and E, the passage h', connecting the compartments E and F, and the gates g and h, applied respectively to the passages b and h', substantially as set forth.

8. The combination of the defecating-compartment D, provided with a partial cover, N, the evaporating-compartment E, provided with cover M, and the finishing-compartment F, substantially as set forth.

25 9. The combination of the defecating-compartment D, provided with a partial cover, N, the evaporating-compartment E, provided with cover M, a bottom passage, b, and a scum-passage, l, connecting said compartments, a finishing-compartment, F, connected with the

evaporating-compartment by a passage, h', and suitable gates whereby the passages b and h' can be opened and closed, substantially as set forth.

35 10. An evaporator having a longitudinal central partition provided with a scum-passage, l, and having the sides and bottom of each compartment constructed of a continuous plate of metal, substantially as set forth.

40 11. An evaporator composed of two longitudinal portions, each having its sides and bottom constructed of a continuous plate of metal and secured to flanged metallic end plates, both portions being secured together side by side, 45 and having a depressed scum-passage, l, formed in their contiguous side plates, substantially as set forth.

12. In an evaporator, the combination of a defecating-compartment, D, an evaporating-compartment, E, a finishing-compartment, F, a scum-passage, l, and flues p p', provided with dampers q' q'', substantially as set forth.

13. The combination, with the defecating-compartment D and evaporating-compartment E, of the scum-passage l, covers M and N, and rounded corner-pieces n, substantially as set forth.
